UNITED STATES PATENT OFFICE.

HARRY B. KANEEN, OF PAPINEAU, ILLINOIS.

TYPEWRITER ATTACHMENT.

Application filed January 19, 1921. Serial No. 438,467.

To all whom it may concern:

Be it known that I, HARRY B. KANEEN, a citizen of the United States, residing at Papineau, in the county of Iroquois and

5 State of Illinois, have invented certain new and useful Improvements in Typewriter Attachments, of which the following is a specification.

This invention relates to new and useful 10 improvements in typewriter attachments, more especially to a paper roll feeding attachment, and the primary object of the invention is to provide a simple and inexpensive attachment, applicable to any make 15 of typewriter whereby paper may be fed from the rolls to the platen of a typewriter, thus eliminating the necessity of feeding separate sheets.

A further object of the invention resides 20 in the provision of an attachment of extremely few and simple parts which may be quickly and readily applied or removed, when desired.

Still another object of the invention resides 25 in the provision of a means for locking the roll of paper to the attachment in such manner that said paper may be unrolled and fed to the platen of the typewriter as said platen rotates in the operation 30 of the typewriter.

A still further object resides in providing 35 a device which is simple and durable in construction, inexpensive to manufacture, and one which will be very efficient and useful in operation.

With these and other objects in view, my invention consists in the novel features of construction, combination and arrangement of parts as will be hereinafter 40 referred to and more particularly pointed out in the specification and claims.

In the accompanying drawing forming a part of this application—

45 Figure 1 is a perspective view showing my improved attachment applied to use;

Fig. 2 is an enlarged detail section through the roll of paper, with parts shown in elevation;

50 Fig. 3 is a detail perspective view of a fragment of the main shaft;

Fig. 4 is a perspective view of the locking sleeve removed;

Fig. 5 is a similar view with the cylinder removed; and

Fig. 6 is a perspective view of the entire 55 roll or cylinder forming the body of the paper roll.

In describing the invention I shall refer to the drawing in which similar reference characters designate corresponding parts 60 throughout the several views, and in which 1 designates the frame of a typewriter of any preferred make which has the carriage 2 operatively mounted thereon, said carriage being provided with the usual platen 65 3. Bolted or otherwise similarly secured to the framework of the carriage, rearwardly of the platen, are the upwardly and rearwardly projecting supporting arms 4. These arms have sockets formed in the 70 upper ends thereof in which are removably mounted the Y-shaped trunnions or supports 5, the latter having bearing balls 6 therein to loosely and rotatably receive the cylindrical ends 7 of the shaft 8 which is 75 designed square in cross section. One cylindrical end of this shaft is threaded in place to the body thereof as shown at 9 so that the parts may be applied and removed, as will be hereinafter referred to, and collars 10 are formed on the cylinder end 7 to abut the outer faces of the Y-shaped supports 5, whereby to prevent longitudinal movement of the shaft therebetween. The extreme ends of the shaft have the knurled 80 85 knobs 11 carried thereon whereby the device may be readily hand-operated when desired.

Carried on the shaft 8 is a cylinder 12, the opening in which is rectangular in cross 90 section to snugly receive the squared portion of the shaft 8, and adapted to be mounted on this cylinder 12 is a roll of paper 13. This paper may be of any preferred size, according to the use to which 95 the same is applied, and the same is preferably perforated as shown at 14 to be readily severed in sheets as the work thereon is completed. The paper is preferably rolled upon the inner cylinder 15 formed 100

preferably of cardboard, the latter being adapted to snugly fit the cylinder 12.

In order to lock the roll of paper on the cylinder 12 a locking means is provided. 5 To this end the cylinder 12 is provided with four rectangular openings 16, said openings being disposed in predetermined positions and adapted for registration with similar openings 17 formed in the roll or 10 cylinder 15. A squared sleeve 18 formed of spring metal is provided, the same having one end thereof slit to provide four spring arms 19, the ends of which are bent outwardly to form locking fingers 20, as 15 clearly shown in Fig. 4. This sleeve is applied to one end of the squared shaft 8 within the cylinder 12, the latter being constructed to receive said sleeve. This sleeve is forced into position within the 20 cylinder so that the fingers 20 spring into openings 16 of said cylinder and simultaneously enter the openings 18 of the roll or cylinder 15, carrying the roll of paper. The sleeve 18 is locked into position by means 25 of a set screw 21 and when properly positioned locks the roll of paper to the shaft so that the latter rotates in its bearings with the rotation of the roll 13.

In operation, after the roll of paper has 30 been properly applied to the shaft 8, the latter is disposed in position on the supporting arms 4 and the paper from the roll 13 is drawn downwardly and fed to the platen 3 of the typewriter, being positioned for writing thereon, as clearly shown in Fig. 1 of the drawing.

After having set the device in this manner, it will be seen as the platen is rotated, the paper will be automatically fed thereto 40 from the roll 13 and as each sheet has been completed the same may be severed from the roll along the perforated portions thereof.

Thus it will be seen that considerable time and labor will be eliminated in that the usual 45 feeding of separate sheets of paper to the machine will be unnecessary. Moreover, it will be seen that this device will provide a means for economy and permit a greater amount of work to be completed than would 50 ordinarily be accomplished through the old methods.

It will still further be seen that I have provided a simple and inexpensive means for carrying out the objects of the invention, and 55 while I have particularly described the elements best adapted to perform the functions set forth, it is obvious that various changes in form, proportion, and in the minor details of construction may be resorted to without departing from the spirit or sacrificing any of the principles of the invention.

Having thus described my invention, what I claim is:

1. An attachment for use with typewriters

or similar carriages, comprising a supporting means, a shaft rotatably mounted in said supporting means, a paper roll on said shaft, and means for removably locking said roll on said shaft. 65

2. An attachment for use with typewriting machine or similar carriages, comprising a supporting means, a shaft rotatably mounted in said supporting means, a cylinder carried on said shaft, a paper roll carried on said cylinder, and means for removably locking said roll to the cylinder. 70

75 3. An attachment for use with typewriting machine or similar carriages, comprising a supporting means, a shaft rotatably mounted in said supporting means, said shaft having a portion thereof designed rectangular in cross section, a cylinder mounted on the rectangular portion of said shaft, a paper roll carried on said cylinder, and means to lock said roll to said cylinder. 80

85 4. An attachment for use with typewriting machine or similar carriages, comprising a supporting means, a shaft rotatably mounted in said supporting means, said shaft having portions thereof rectangular in cross section, a cylinder slidably mounted on the rectangular portion of said shaft, a paper roll mounted on said cylinder, and means to lock the cylinder against longitudinal movement on the shaft and simultaneously lock 90 said roll to the cylinder. 95

100 5. In a device of the class described, the combination with supporting means; of a rotatable shaft having a portion thereof designed rectangular in cross section, a cylinder slidably mounted on the rectangular portion of the shaft, a paper roll mounted on said cylinder, and a locking sleeve carried on said shaft retaining said cylinder against longitudinal movement on the shaft and simultaneously securing the roll to said cylinder. 105

110 6. In a device of the class described, the combination with supporting means; of a rotatable shaft having a portion thereof designed rectangular in cross section, a cylinder slidably mounted on the rectangular portion of said shaft and provided with a plurality of radial openings, a tubular member slidably mounted on said cylinder and provided with additional openings adapted to register with the aforesaid openings of the cylinder, a paper roll applied to said tubular member, a locking device removably applied to the rectangular portion of said shaft and provided with means to lock the cylinder against longitudinal movement on the shaft and simultaneously secure said tubular member and the paper roll to said cylinder. 115

120 125 7. In a device of the class described, the combination with supporting means; of a rotatable shaft having a portion thereof designed rectangular in cross section, a cylin-

der slidably mounted on the rectangular portion of said shaft and provided with a plurality of radial openings, a tubular member slidably mounted on said cylinder and provided with additional openings adapted to register with the aforesaid openings of the cylinder, a paper roll applied to said tubular member, and a sleeve removably applied to the rectangular portion of the shaft and hav-

ing locking fingers formed thereon adapted to enter the registering openings in said cylinder and tubular member whereby to secure the same one to the other and simultaneously lock said cylinder against longitudinal movement on the shaft.

15

In testimony whereof I affix my signature.

HARRY B. KANEEN.
